[57] CLAIM

The ornamental design for velocipede horn, substantially as shown and described.

DESCRIPTION

FIG. 1 is a front perspective view of a velocipede horn showing our new design, a child's tricycle being shown in broken lines for illustrative purposes only;

FIG. 2 is a top plan view thereof;

FIG. 3 is a bottom plan view thereof;

FIG. 4 is a side elevational view taken from the right of FIG. 1;

FIG. 5 is a front elevational view thereof;

FIG. 6 is a side elevational view taken from the left of FIG. 1; and

FIG. 7 is a rear elevational view thereof.

FIG. 1FIG. 2FIG. 3FIG. 4FIG. 5FIG. 6FIG. 7
